UNITED STATES PATENT OFFICE

JOHN THOMAS WILSON, OF JERSEY SHORE, PENNSYLVANIA.

PACKING FOR PISTONS AND PISTON-VALVES.

No. 898,617.

Specification of Letters Patent.

Patented Sept. 15, 1908.

Application filed October 3, 1904. Serial No. 226,902.

To all whom it may concern:

Be it known that I, JOHN THOMAS WILSON, a citizen of the United States, residing at Jersey Shore, in the county of Lycoming and State of Pennsylvania, have invented new and useful Improvements in Packing for Pistons and Piston-Valves, of which the following is a specification.

The invention relates generally to packings for pistons and piston valves, and especially to a packing for a piston valve, the object being the production of a packing which will enable the valve to travel over ports that have no bridges or relatively few bridges, which shall have the snap rings so held that they cannot excessively expand into the port, or become loose when the engine is drifting or not working steam and move backwardly and forwardly at their exposed edges, or become tilted and the edges catch the edges of the port, which shall not leak motive fluid, and which, withal, shall constitute a superior means for performing the requisite functions of a perfect piston valve and obviate the imperfections appertaining to this type of valve now in use.

The invention consists broadly in a packing comprising a wide ring in engagement with two snap rings in such a manner that the snap rings cannot excessively expand into a port.

Finally, it consists in certain novelties of construction and combinations of parts as hereinafter set forth and specified in the claims.

The accompanying drawing illustrates an example of the physical embodiment of the invention constructed according to the best mode I have so far devised for the practical application of the principle.

Figure 1 is a longitudinal vertical section of one half of a piston valve, the section of the packing at the top being on line 1-1 Fig. 2. Fig. 2 is a section of the packing showing the lap joints of the snap rings. Fig. 3 is a side view of Fig. 2 broken away to show the location of the rivets. Fig. 4 is a section of the packing on line 4-4 Fig. 2. Fig. 5 shows the free ends of the wide ring.

Referring to the several figures, the numeral 1 designates the body of a valve spool of any approved type or shape; 2, a flange upon the body; 3, the removable end of the spool; 4, a circular flange; 5, the valve stem; 6, a bull ring located in the space between the flanges 2 and 3 as shown; 7, the flanges

of the bull ring bearing against the inner surfaces of the flanges; 8, the snap rings; 9, the outwardly projecting flanges of the snap rings; 10, grooves in the inner vertical surfaces of the snap rings; 11, the lap joints; 12, the lap plates at the bottom of the joints; 13, rivets which secure one end of each plate to the body of a ring; 14, the wide ring; 15, the tenoned edges of the wide ring; 16, the free ends of the wide ring; 17, holes through the body of the wide ring; 18, the space beneath the inner snap ring; 19, a hole in the flange 2, communicating with the space 18 as shown; 20, the space beneath the outer snap ring; 21, the space beneath the wide ring; and 22 is a passage through the bull ring for opening communication between the space 20 and space 21, as illustrated.

The mode of operation when the engine is working steam is as follows: Assuming the end of the piston valve shown to be moving toward the left and to a port, the inner snap ring is forced outwardly by steam which enters passage 19 and is at all times beneath the snap ring. When the port is opened steam enters and passes through holes 17 and through passages 22, so that the outer edge of the wide ring and outer snap ring are forced against the surface of the lining or cage, the same having passed the edge of the port. When the entire packing has passed the port confined steam beneath the wide and outer snap rings holds them against the lining. When the valve has moved toward the right and over the port steam enters beneath the wide ring and balances it and upon further travel the exhaust is opened and the steam escapes from beneath the outer snap and wide rings to the atmosphere. At the extreme position of the valve to the right, steam pressure is only beneath the inner snap ring.

It will be observed that the inner snap ring, at all times forced outwardly by steam pressure, maintains a tight joint, but that the outer snap ring and outer edge of the wide ring are expanded by steam pressure only when beyond the left edge of the port. As the width of the packing is wider than the width of the port the snap rings will not be expanded into the port, as they are held by the wide ring or locked to it and consequently the valve can be used with a port without bridges or with relatively few bridges. In practice however it may be desirable to provide two bridges and locate the joints of the

2
snap rings and the free ends of the wide ring in line with these bridges so that in moving across the port the joints will be held in their normal positions.

5 From the foregoing description taken in connection with the drawings it becomes clear that I have provided a packing which fulfills all the conditions set forth as the object of my invention.

10 Heretofore attempts have been made to use a wide steam expansible packing ring but when upon either side of the port the friction has been excessive, and when over the port the ring would collapse and leak. Solid 15 wide rings or rings bolted together at the ends have been tried but all have been abandoned on account of leakage or excessive friction.

My improvement is designed to obviate the imperfections of former constructions.

20 While I have illustrated and described only one example of the physical embodiment of my invention, I do not thereby intend to restrict its scope to such example as in practice changes may be introduced which will embody the principle and not constitute substantial departures.

What I claim as new and desire to secure by Letters Patent is:

1. A packing for pistons and piston valves comprising a wide ring and two snap rings 30 interlocked, each of said snap rings being substantially in one piece and expansible.

2. The combination with a piston or piston valve, of a packing comprising two snap 35 rings and a wide ring between the snap rings and positively engaging said rings, but movable relative to said snap rings, each of said snap rings being expansible.

3. The combination with a piston or piston 40 valve, of a packing comprising two snap rings, and a wide ring; the said rings having tongues and grooves.

4. The combination with a piston or piston valve, of two snap rings, a wide ring, and a 45 bull ring.

5. The combination with a piston or piston valve, of a packing comprising two expansible snap rings each being substantially in one piece, and a wide ring positively engaging the snap rings, and means for introducing motive fluid beneath one of the snap 50 rings.

6. The combination with a piston or piston valve, of two snap rings and a wide ring,

means being provided for introducing motive fluid through the wide ring and to its inner surface when the same is in communication with a port.

7. The combination with a piston or piston valve, of two snap rings and a wide ring; 60 means as holes 17 and passage 22 being provided for introducing motive fluid beneath the wide ring and one snap ring when the wide ring is in communication with a port.

8. The combination with a piston or piston valve, of two snap rings, and a wide ring; 65 means as hole 19 and hole 17, being provided for introducing motive fluid beneath one snap ring when steam is in use, and beneath the wide ring when the same is in communication with a port.

9. The combination with a piston or piston valve, of two snap rings, and a wide ring; 70 means as hole 19, hole 17 and passage 22, being provided for introducing steam under 75 one snap ring continuously, and beneath the wide ring and the other snap ring when the wide ring is in communication with a port.

10. The combination with a piston or piston valve, of a packing comprising three 80 movable interlocking rings; and means for introducing motive fluid under one edge of the packing when the engine is working steam.

11. The combination with a piston or piston valve, of a packing comprising two snap rings and a central ring; and means for introducing steam through the packing when the same is in communication with a port.

12. The combination with a piston or piston valve, of a packing, and means as hole 19 and hole 22 for introducing steam continuously beneath one edge of the packing, and beneath the opposite edge of the packing only when the same is in communication 95 with a port.

13. The combination with a piston or piston valve, of a packing comprising two snap rings each having a groove in its side, and a wide ring with its edges located in the 100 grooves and movable therein.

In testimony whereof I affix my signature in presence of two witnesses.

JOHN THOMAS WILSON.
